LEATHER WORKING MACHINE

Gustav Adolf Schettler, Leeds, England, assignor
to The Turner Tanning Machinery Company,
Portland, Maine, a corporation of Maine

Application June 16, 1928, Serial No. 285,857,
and in Great Britain July 20, 1927

20 Claims. (Cl. 149—16)

This invention relates to machines for operating upon hides, skins, leather and other similar pieces of work and is illustrated as embodied in a machine for setting hides or putting-out skins.

It is to be understood, however, that the invention and various important features thereof may have other applications and uses.

It has heretofore been proposed to provide machines of the type referred to with a roll located below the bed roll of the machine in spaced relation thereto to serve as an auxiliary work support, the bed roll and the auxiliary work support operating to tension the work and to support it in such a manner as to present a considerable surface of the work under tension to an operating cylinder. In the described prior construction, the bed roll and the auxiliary roll are each driven in a positive manner by gearing, part of which is supported on the frame of the machine while other parts move with the bed roll and auxiliary roll, respectively. It is a disadvantage of such prior constructions that the drive of the auxiliary roll is positive with no possibility of adjusting the tension on the work suitably to the requirements thereof. Moreover, the meshing of the independent gears may not be simultaneous so that the auxiliary roll may not be applying tension to the work at the instant that the work operating cylinder is reached by the work on the bed roll.

It is an object of the invention to provide a machine of the character described which will obviate the disadvantages of prior constructions and will be simpler and more durable in its construction.

To these ends and in accordance with a feature of the invention, the illustrated machine comprises an auxiliary roll co-operating with a bed roll and arranged to be driven impositively in a direction the reverse of the direction of rotation of the bed roll, thereby placing the material under tension, but not a positively unyielding tension, where it is being operated upon by a work operating instrumentality. Conveniently, the auxiliary member is driven frictionally by contact of its cylindrical surface with corresponding surface of the bed roll and hence is operative and effective to tension the work the instant the bed roll becomes operative to back the work against the thrust of the work operating instrumentality. Since the auxiliary roll is adjustable with respect to the bed roll, the pressure between them can be predetermined, in this way predetermining also the maximum tension on the work. If the quality of the work should require extreme tension, the auxiliary roll may be adjusted so firmly in con-

tact with the bed roll as to secure such tension, whereas work of a more stretchable quality may have less tension applied by driving the auxiliary roll with less pressure on the bed roll so that it may slip when the tension reaches a predetermined maximum. Another advantage of the construction by which the auxiliary roll is caused to press against the bed roll, instead of being in spaced relation thereto as in prior constructions, resides in the fact that waste liquids are thereby prevented from being carried by the bed roll into contact with the work. In the illustrated machine also, the auxiliary roll is pressed yieldingly against the work operating instrumentality, the degree of pressure being readily controllable so that the operator may secure the proper pressure at will by a simple manipulation of a hand lever provided for the purpose.

These and other features of the invention, including various details of construction and combinations of parts, will be more particularly described by reference to the accompanying drawing and thereafter pointed out in the claims.

In the drawing,

Fig. 1 is a view in front elevation of a machine embodying the invention in a preferred form;

Fig. 2 is a sectional view along the line II—II of the machine shown in Fig. 1;

Fig. 3 is a detail view illustrating an arrangement for yieldingly mounting the auxiliary work supporting roll; and

Fig. 4 is an end view of the machine shown in Fig. 1 illustrating the means for moving the bed roll and auxiliary roll between work receiving and work presenting positions.

In the illustrated machine, which is adapted, among other uses such as those later mentioned, for the operations of putting-out skins and setting hides after tanning operations, there is provided a bed roll 10 for presenting pieces of work to an operating instrumentality consisting of a bladed cylinder 12. In order that the bed roll may move between work receiving and work presenting positions it is mounted at the upper end of oscillatory arms 14 (Fig. 4) arranged to be operated by toggle members 16, 18 from a shaft 20 through pitmans 22, in a well-known manner. Preferably and as shown, one end of the toggle member 18 is pivoted to a rod 24 backed yieldingly by a heavy spring 26 mounted slidably in a box 28 carried by the machine frame, so that the bed roll 10 may yield when in operative position to accommodate variations in the thickness of the pieces of work.

When the bed roll 10 moves to work presenting

position a gear 29 on its shaft comes into mesh with a constantly driven gear 31 on the shaft of a feed roll 30 mounted above and in front of the bladed cylinder 12 in journals provided in the frame of the machine. The feed roll 30 is arranged to be driven in the direction of the arrow to co-operate with the bed roll 10 in feeding the piece of work toward the operator while the bladed cylinder 12 rotates in a direction opposed to the feeding direction of the work to operate upon the work where it is backed by the bed roll. The arrangement of rolls 10 and 30 with respect to each other and with respect to the bladed cylinder 12 is such that the piece of work is gripped to effect feeding thereof just before the bed roll presses the work against the bladed cylinder. As indicated in Fig. 1, the cylinder 12 is driven continuously at a uniform speed by power applied through pulley 33 on the shaft of the cylinder and keyed thereto.

In introducing a piece of work into the machine, it is thrown over the bed roll 10 so that approximately one-half of the hide or skin will be operated upon while it is being fed out in a forward direction toward the operator. When this operation is completed the operator steps upon treadle 31, causing the bed roll to move to open, work receiving position. The piece of work is then reversed end for end and the untreated part is thrown over the bed roll 10 in position for the bladed cylinder 12 to begin its operation upon the untreated portion.

For assisting the bed roll 10 in presenting the work to the bladed cylinder 12 there is provided an auxiliary roll 32 carried in journals provided in swing arms 34 mounted for oscillation one at each end of the shaft 36 of the bed roll 10, the roll 32 being substantially equal in length to the roll 10. From this arrangement it will be clear that the auxiliary roll 32 moves with the bed roll 10 between work receiving and work presenting positions. It will be observed also (Figs. 2 and 4) that the immediate support for the auxiliary roll 32 is furnished by a pair of auxiliary swing arms 40 each pivoted at 42 upon the swing arms 34.

For pressing the auxiliary roll 32 more or less firmly into contact with the bed roll 10 there is provided at each end of the roll 32 a member 44 screw threaded into a boss 46 on the arm 34 and having an end portion for engagement with the auxiliary swing arm 40. Upon proper manipulation of the screw threaded members 44 the roll 32 is forced more or less firmly against the bed roll 10 as may be desirable, and is locked in adjusted position by lock nuts 48. By this contact with the bed roll the auxiliary roll is driven frictionally by the bed roll in a direction the reverse of the direction of movement of the bed roll, thereby causing the auxiliary roll to apply considerable tension to the work. Only moderate pressure between the two rolls is required to drive the auxiliary roll. On the other hand, the auxiliary roll will slip when tension on the work of a predetermined maximum is reached. Hence, the amount of tension on the work is automatically controlled by the driving connections between the auxiliary roll 32 and the bed roll 10.

Inasmuch as, in unhairing and in fleshing operations, the hide or skin should be under tension to secure the best results, the present construction and arrangement of the bed roll and its auxiliary roll provide a construction especially suited for these two operations as well as for operations such as those above mentioned. Moreover, the driving of the auxiliary roll 32 by the bed roll

10 in the manner described makes it unnecessary to provide a separate driving means for the auxiliary roll, thus doing away with the gearing characteristic of prior constructions, in which a gear on the shaft of the auxiliary roll had to come into mesh with a gear stationary in space on the frame of the machine. As a further advantage, the auxiliary roll 32, through its firm rolling contact with the bed roll 10, serves to prevent the passage of water and other liquids from the back of the bed roll, i. e., the work presenting surface opposed to the cylinder, to the work supporting face thereof, thus assisting in keeping the work in a cleanly condition.

For holding the swing arms 34 positioned to cause the auxiliary roll 32 to press the work against the bladed cylinder 12 each swing arm 34 is provided at its upper end with a connecting link 50 pivotally mounted upon a shaft 52, the ends of which are supported in bearings furnished by brackets 54 secured to the frame of the machine. At its other end each connecting link 50 is pivotally connected at 56 to the adjacent end of one of the swing arms 34. Preferably, and as shown, the connecting link 50 comprises a portion 58 which may be manipulated to cause desired variations in the length of the link so that the auxiliary roll 32 may be positioned in the desired initial relation with respect to the bladed cylinder 12. In order that the pressure of the auxiliary roll 32 with respect to the bladed cylinder 12 may be adjusted instantly at the will of the operator, the connecting links 50 are each provided with a portion 60 engaged with an eccentric strap member 62 surrounding an eccentric 63 on the shaft 52. Secured to the shaft 52 at one end is a hand lever 64. Upon rotating the shaft 52 by means of the hand lever 64, the eccentrics at each end thereof are shifted to cause movement of the links 50 and, perforce, of the swing arms 34 about their pivots on the shaft 36. In this way the auxiliary roll 32 may be moved toward or from the bladed cylinders 12, thereby varying the pressure of the auxiliary roll 32 upon the work between it and the bladed cylinder. For holding the hand lever 64 and with it the shaft 54 in adjusted position, there is provided a quadrant 66 fast to the bracket 54 and having a slot 68 struck on an arc about the center of the shaft 52. Projecting through the handle lever 64 and through the slot 68 is a bolt 70 having a winged nut 72 associated therewith for tightening the bolt to hold the handle 64 in adjusted position with respect to the quadrant 66.

In order that the auxiliary roll 32 may be pressed yieldingly against the bladed cylinder 12, the connection between the shaft 52 and the adjacent end of the swing arm 34 may be yielding, as illustrated in Figs. 2 and 4 wherein it will be seen that the connecting link 50, pivoted at 56 to the swing arm 34, has its other end 60 slidably mounted within the strap member 62, a spring 88 interposed between a washer 90 in engagement with the strap member 62 and a second washer 92 backed by an adjustable nut 94 screw threaded upon the screw threaded portion 58 of the connecting link 50. It will be clear upon inspection of Fig. 2 that a thicker portion in the piece of work will cause the auxiliary roll 32 to yield away from the bladed cylinder 12 since the springs 88 will shorten under the compression force exerted by the washers 92 carried by the connecting links 50. At the same time rotation of the shaft 52 by the handle lever 64 will cause adjustment of the link 50 and of the

swing arm 34 if no work is interposed between the roll 32 and the cylinder 12. In case the hand lever 64 is adjusted while a piece of work is on or passing over the roll 32, the yielding pressure applied through the springs 88 will be varied.

If desired, the auxiliary roll 32 may be mounted at each end in a bearing block 100 (Fig. 3) slidably supported in the adjacent end of the swing arm 34, the bearing blocks 100 each having above and below forked portions to engage slidably with adjacent portions of the swing arm 34 and each block 100 being pressed upon by a spring 102 interposed between the block and a boss 104 formed as part of the lower end of the swing arm 34. Extending through the boss 104 is a member 106 having its other end screw threaded into the block 100, the arrangement being such that the spring 102 surrounds the member 106 to be held in proper position thereby. For holding the block 100 against the pressure of the spring 102 the member 106 is screw threaded upon its free end to receive two nuts 108. These nuts prevent movement of the block 100 and of the auxiliary roll 32 toward the bladed cylinder 12 under pressure of the spring 102. At the same time, the roll 32 and blocks 100 may move toward the left in Fig. 3, compressing the springs 102 in self-adjusting movements of the roll 32 in accommodation to variations in the thickness of the work passing between the roll and the bladed cylinder 12. In the construction shown in Fig. 3 for pressing the auxiliary roll 32 more or less firmly against the bed roll 10, there is provided a screw threaded member 110 in all essential respects similar to the screw threaded member 44 shown in Fig. 2.

In the operation of the machine, the auxiliary roll 32 is driven, as already stated, through its contact with the bed roll 10 to rotate in a direction the reverse of the direction of rotation of the bed roll. Hence, a piece of work resting over both the bed roll 10 and the auxiliary roll 32 will be subjected to a stretching operation which opens out the shank and skirt portions of the hides or skins, extends folded or wrinkled portions wherever occurring in the work, and places both sides of the hide or skin under practically equal tension. If, for instance, the grain side of a hide or skin be presented to the bladed cylinder 12, it will be subjected to a very considerable stretching effect by the bladed cylinder at the same time that it is being operated upon by the blades in their special capacity as putting-out or setting blades. Now, by providing for driving the auxiliary roll 32 in a direction the reverse of the bed roll 10, the flesh side of the same hide or skin is put under tension practically the same in amount as the tension on the grain side. This is particularly important in operations upon sheep skins wherein differences in tension on the grain and flesh sides of the same piece of work may result in piping, that is, separation of the grain side from the flesh side. By providing for adjustment of the pressure between the bed roll and auxiliary roll, the tension may be varied to suit the requirements of the work in the manner already described.

Having described my invention, what I claim as new and desire to secure by Letters Patent of the United States is:

1. In a machine for operating upon hides, skins, leather and other similar pieces of work, an instrumentality for operating on a piece of work, a driven work supporting bed roll, and an auxiliary roll arranged to present a surface to back the

piece of work directly against the thrust of said instrumentality, said auxiliary roll being driven impositively from the bed roll in a direction the reverse of the direction of the rotation of the bed roll, whereby the work supporting surfaces of the bed and auxiliary rolls move in opposite directions to tension the work during the operation of said instrumentality.

2. In a machine for operating upon hides, skins, leather and other similar pieces of work, an instrumentality for operating on a piece of work, a driven work supporting bed roll, and an auxiliary work supporting roll having a surface arranged to back the work against the thrust of said instrumentality, said auxiliary roll having its cylindrical surface in contact with the cylindrical surface of the bed roll, so as to be driven frictionally from the bed roll whereby the work supporting surfaces of the bed and auxiliary rolls move in opposite directions to apply tension to the work during the operation of said instrumentality.

3. In a machine for operating upon hides, skins, leather and other similar pieces of work, an instrumentality for operating on a piece of work, a driven work supporting bed roll, an auxiliary work supporting roll arranged to back the work against the thrust of said instrumentality, and means for mounting the auxiliary roll with its surface in contact with the bed roll to cause the auxiliary roll to be driven frictionally by the bed roll, the two rolls being adjustable with respect to each other to predetermine the pressure between them.

4. In a machine for operating upon hides, skins, leather and other similar pieces of work, an instrumentality for operating on the work, means for feeding the work comprising a work support for backing the work against the thrust of the operating instrumentality, means for tensioning the work while it is undergoing treatment by the operating instrumentality, means for pivotally mounting the tensioning means with respect to the feeding means, said tensioning means comprising a roll driven from the feeding means, and connections between said roll and the feeding means arranged to adjust the roll about its pivotal mounting means in directions toward or from the feeding means thereby to determine the tension applied to the work.

5. In a machine for operating upon hides, skins, leather and other similar pieces of work, a bladed cylinder for operating on the work, a driven work supporting bed roll, and an auxiliary roll driven by the bed roll to turn in a direction the reverse of that of the bed roll for tensioning the piece of work for the bladed cylinder during the operation of the latter.

6. In a machine for operating upon hides, skins, leather and other similar pieces of work, a bladed cylinder for operating on the work, a bed roll for supporting the work against the thrust of the bladed cylinder, and an auxiliary work supporting roll having a surface arranged to back the work against the thrust of said cylinder, said auxiliary roll located in rolling contact with the bed roll and operative to prevent passage of waste liquids to the work supporting surface of the bed roll from the rear or work presenting surface of the bed roll where it is opposed to the cylinder.

7. In a machine for operating upon hides, skins, leather and other similar pieces of work, a bladed cylinder for operating on a piece of work, a bed roll for backing the work against the thrust of the cylinder, a feed roll arranged to

- cooperate with the bed roll to feed the work, means driven in a direction the reverse of that of the bed roll for tensioning the work while it is undergoing operation by the cylinder, and connections between the tensioning means and the bed roll arranged to adjust the former directly toward or from the latter thereby to determine the tension applied to the work.
8. In a machine for operating upon hides, skins, leather and other similar pieces of work, a bladed cylinder operating on a piece of work, means for feeding the work comprising a work support arranged to back the work directly against the thrust of the cylinder, an auxiliary roll operative to pull the work in a direction opposite to the feeding means for tensioning it during the operation of the cylinder, and connections between the auxiliary roll and the work support arranged to adjust the former directly toward or from the latter thereby to determine the tension applied to the work.
9. In a machine for operating upon hides, skins, leather and other similar pieces of work, a bladed cylinder for operating on a piece of work, a driven work supporting bed roll, and means driven directly by the bed roll for tensioning the work for the bladed cylinder during operation of the latter.
10. In a machine for operating upon hides, skins, leather and other similar pieces of work, a bladed cylinder for operating on a piece of work, a bed roll for supporting the work against the thrust of the cylinder, means for feeding the work past the bladed cylinder, and a roll positioned to have the work dragged over a surface thereof, said last-mentioned roll turning in a direction the reverse of that of the bed roll and arranged to be driven directly by the bed roll to tension the piece of work during the operation of the bladed cylinder.
11. In a machine for operating upon hides, skins, leather and other similar pieces of work, a bladed cylinder for operating on the work, means for feeding the work past the bladed cylinder comprising a bed roll for supporting the work against the thrust of the cylinder, an auxiliary work supporting roll driven in a direction the reverse of the bladed cylinder to co-operate therewith in tensioning the work during the operation of the cylinder thereon, and means arranged to operate upon the auxiliary roll independently of the bed roll for yieldingly pressing the auxiliary roll in a direction toward the bladed cylinder, said auxiliary roll being mounted for adjustment directly toward or from the bed roll.
12. In a machine for operating upon hides, skins, leather and other similar pieces of work, a bladed cylinder for operating on a piece of work, a bed roll for supporting the work against the thrust of the bladed cylinder, means for supporting the bed roll for movement between work receiving and work presenting positions, an auxiliary work supporting roll for co-operation with the bed roll in tensioning the work, means for yieldingly backing the bed roll so as to accommodate variations in the thickness of the work between the bed roll and the bladed cylinder, means independent of the yielding backing of the bed roll for yieldingly backing the auxiliary roll against the thrust of the cylinder upon the work, and means arranged to adjust the auxiliary roll directly toward or from the bed roll for varying the tension on the work.
13. In a machine for operating upon hides, skins, leather and other similar pieces of work,
- a bladed cylinder for operating on a piece of work, a bed roll for supporting the work against the thrust of a bladed cylinder, an auxiliary roll for supporting the work against the thrust of the cylinder, said auxiliary roll being driven from said bed roll, means for yieldingly backing the bed roll so as to accommodate variations in the thickness of the work between the bed roll and the bladed cylinder, and means independent of the yielding backing of the bed roll for supporting the auxiliary roll adjustably with respect to the bladed cylinder.
14. In a machine for operating upon hides, skins, leather and other similar pieces of work, a bladed cylinder for operating on a piece of work, a bed roll for supporting the work against the thrust of the bladed cylinder, means for supporting the bed roll for movement between work receiving and work presenting positions, an auxiliary work supporting roll driven from the bed roll and movable with the bed roll between work receiving position and work presenting position with respect to cylinder, means for yieldingly backing the bed roll so as to accommodate variations in the thickness of the work between the bed roll and the bladed cylinder, and means independent of the yielding backing of the bed roll for supporting the auxiliary roll adjustably with respect to the bladed cylinder.
15. In a machine for operating upon hides, skins, leather and other similar pieces of work, a bladed cylinder for operating on a piece of work, a driven work supporting bed roll, operative to support the work against the thrust of the bladed cylinder, an auxiliary work supporting roll arranged to be driven in a direction the reverse of that of the bed roll to put the work under tension where it is being operated upon by the cylinder, means for yieldingly backing the bed roll so as to accommodate variations in the thickness of the work between the bed roll and the bladed cylinder, and means readily operable by the operator for adjusting the auxiliary roll with respect to the bladed cylinder during the operation of the machine.
16. In a machine for operating upon hides, skins, leather and other similar pieces of work, a bladed cylinder for operating on a piece of work, a driven work supporting bed roll, means for supporting the bed roll for movement between work receiving and work presenting positions, an auxiliary work supporting roll movable with the bed roll between work receiving and work presenting positions, said auxiliary roll being arranged to back the work against the thrust of the cylinder, and means for yieldingly backing the bed roll so as to accommodate variations in the thickness of the work between the bed roll and the bladed cylinder, the auxiliary roll being driven from the bed roll in a direction the reverse of that of the bed roll to tension the piece of work during the operation of the bladed cylinder.
17. In a machine for operating upon hides, skins, leather and other similar pieces of work, a bladed cylinder for operating on a piece of work, a driven work supporting bed roll operative to back the work against the thrust of the bladed cylinder, means for supporting the bed roll for movement between work receiving and work presenting positions, an auxiliary work supporting roll movable with the bed roll between work receiving and work presenting positions, means for yieldingly backing the bed roll so as to accommodate variations in the thickness of the work between the bed roll and the bladed cylinder, the auxiliary roll being driven from the bed roll in a direction the reverse of that of the bed roll to tension the piece of work during the operation of the bladed cylinder.

the work between the bed roll and the bladed cylinder, and means for supporting the auxiliary roll in contact with the bed roll so as to be driven thereby, said supporting means being constructed and arranged to permit the auxiliary roll to yield relatively to the bladed cylinder.

18. In a machine for operating upon hides, skins, leather and other similar pieces of work, a bladed cylinder for operating on a piece of work, a bed roll for supporting the work against the thrust of the bladed cylinder, means for driving the bed roll, means comprising oscillatory members for supporting the bed roll for movement between work receiving and work presenting positions, swing arms mounted to turn about the axis of the bed roll and to move therewith during movement of the bed roll between work receiving and work presenting positions, an auxiliary work supporting roll carried by said swing arms and arranged to be driven by the bed roll, and means connected with the swing arms on the side of the bed roll away from the auxiliary roll for holding the auxiliary work supporting roll yieldingly against the thrust of the bladed cylinder.

19. In a machine for operating upon hides, skins, leather and other similar pieces of work, a bladed cylinder for operating on a piece of work, a bed roll for supporting the work against the thrust of the bladed cylinder, means comprising oscillatory members for supporting the bed roll for movement between work receiving and work presenting positions, swing arms mounted to turn about the axis of the bed roll and to move therewith during movement of the bed roll between work receiving and work presenting positions, an auxiliary work supporting roll carried by said swing arms, means to press the

auxiliary roll yieldingly toward the cylinder, a shaft mounted in the frame of the machine, and connecting links movable on the shaft and pivotally connected to the swing arms, said links being operative to cause the auxiliary work supporting roll to be held by the swing arms in position to support the work against the thrust of the bladed cylinder, said shaft being movable to adjust the connecting links, whereby the yielding pressure of the auxiliary roll with respect to the cylinder may be varied.

20. In a machine for operating upon hides, skins, leather and other similar pieces of work, a bladed cylinder for operating on a piece of work, a bed roll for supporting the work against the thrust of the bladed cylinder, means comprising oscillatory members for supporting the bed roll for movement between work receiving and work presenting positions, an auxiliary work supporting roll, swing arms mounted to turn about the axis of the bed roll and to move therewith during movement of the bed roll between work receiving and work presenting positions, said swing arms being provided with bearings for supporting the auxiliary work supporting roll, a shaft mounted in the frame of the machine, connecting links movable on the shaft and pivotally connected to the swing arms, and spring means associated with said links to hold the swing arms with the auxiliary work supporting roll pressed yieldingly against the thrust of the bladed cylinder, and said connecting links being adjustable with respect to the shaft to control the spring means to vary the yielding pressure of the work supporting auxiliary roll with respect to the bladed cylinder.
